ONE HAND COMPACT

Charles Weeks, Des Moines, Iowa, assignor to
The Armand Company, Des Moines, Iowa, a
corporation of Iowa

Application January 24, 1934, Serial No. 708,061

4 Claims. (Cl. 132—83)

An object of my present invention is to provide a compact which can be operated by one hand of the user and yet which is comparatively simple and inexpensive to manufacture.

5 A further object is to provide a compact for cosmetics and the like which can be held in one hand of the user by the thumb on one side of the compact and three fingers on the other side, the index finger being utilized to engage a portion of the compact and move such portion to either open or close the compact.

Still a further object is to provide a mirror which swings to extended position as the compact is opened and which is swung to its inner concealed position as the compact is closed.

15 With these and other objects in view my invention consists in the construction, arrangement and combination of the various parts of my device, whereby the objects contemplated are attained, as hereinafter more fully set forth, pointed out in my claims, and illustrated in the accompanying drawing, in which:

Figure 1 is a perspective view of a compact embodying my invention.

25 Figure 2 is a side elevation of the same, parts being broken away and the compact being shown partly opened.

Figure 3 is a sectional view on the line 3—3 of Figure 1; and

30 Figure 4 is a sectional view on the line 4—4 of Figure 3 with the parts in a different position.

On the accompanying drawing, I have used the reference character A to indicate a compact for cosmetics and the like. It has a pair of sides 35 10 and 12, a front face 14, a back face 16 and ends 18 and 20. In the front face 14, I provide an opening 22 which is normally closed by a sheet of flexible material 24.

The material 24 may be either opaque or transparent celluloid or a suitable heavy cellophane product or the like, the main characteristic being that it is flexible, yet stiff enough to be pushed along guides by engaging one end of it.

40 Guides are provided for the cover element 24 in the form of angle members 26 which are arranged adjacent the sides of the opening 22 as shown in Figures 2 and 4. These may be spot welded or otherwise suitably secured to the sides 10 and 12 of the compact A. A second guide element consists of a curved strip of metal 28 forming a continuation of the guide elements 26, or if found feasible, it can be integrally formed therewith. The guide element 28 is arranged adjacent the end wall 18 as best shown 45 in Figure 3. A third guide element is arranged

adjacent the back face 16 and may take the form of a powder receptacle 30, if desired.

The back face 16 of the compact A is provided with a slot 32. One end of the flexible cover element 24 is provided with a projection 34 in the form of a button extending through the slot 32.

5 A mirror element 36 is provided and it is swingably mounted. For instance, it may be set in a metal socket 38 having pintles 40, or it can be formed of polished sheet metal if desired.

10 On one of the pintles, a spring 42 is arranged for the purpose of constraining the mirror 36 to swing from its inner position shown by full lines in Figure 3 to its outer position shown by dotted lines therein.

15 In the operation of the compact, it may be held in one hand, usually the left hand, by engaging the thumb with the side 12 and the last three fingers of the hand with the side 10. The first or index finger may then be engaged with the button 34 and move it from the full line position to the dotted line position of Figure 3, which will shift the cover element 24 from a position within the guides 26 and 28 to a position within the guides 28 and between the powder receptacle 30 20 and the back face 16.

25 During this operation, the mirror element 36 will swing to the dotted line position, an intermediate position being shown in Figure 2. It is then in position for use and a powder puff 44 30 normally resting between the mirror element and the receptacle 30 can be removed for use. After powder puff is replaced, it is a simple matter to slide the button 34 from the dotted line position to the full line position of Figure 3, which will 35 first swing the mirror 36 to its inner position and then project the flexible element 24 across the opening 22 to close the compact.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

40 I claim as my invention:

1. A compact adapted to be supported and operated by one hand comprising a relatively flat container having a top face provided with an opening, a bottom face, two ends and two sides, a closure element for said opening comprising a flexible element normally extending across said opening and across one of said ends, a slot in said bottom face and extending from end to end of said container and a projection on one end of said 50 55

flexible element, extending through said slot and normally at the end thereof, adjacent the end across which said flexible element extends and adapted to be moved to the other end of said slot for withdrawing said flexible element from closing position with relation to said opening, guide elements inside of said flexible element and along said top face, pivot means inward of said guide elements, a mirror pivoted to said pivot means and spring means tending to swing said mirror outwardly through said opening between said guide elements.

2. A compact comprising a relatively flat container having a top face provided with an opening, a bottom face, two ends and two sides, a closure element for said opening comprising a flexible element normally extending across said opening and across one of said ends, a projection on one end of said flexible element for withdrawing said flexible element from closing position with relation to said opening, guide elements inside of said flexible element and along said top face, pivot means inward of said guide elements, a mirror pivoted to said pivot means and spring means tending to swing said mirror outwardly through said opening between said guide elements.

3. A compact comprising a relatively flat container having a top face provided with an opening, a bottom face, two ends and two sides, a closure element for said opening comprising a flexible member normally extending across said opening and across one of said ends, means for guiding said flexible member relative to said opening comprising stationary guide elements spaced from

said top face and arranged adjacent the edges of said opening for guiding and supporting the edges of said flexible member, a projection on one end of said flexible member for withdrawing it from closing position with relation to said opening and means for supporting said flexible member intermediate the guided edges thereof comprising a hinged element normally constrained to swing to open position through the opening of said top face and between said guide elements and engageable by said flexible member when it is moved to closed position for swinging the hinged element to closed position wherein it supports said flexible member when closed.

4. A compact comprising a relatively flat container having a top face provided with an opening, a bottom face, two ends and two sides, a closure element for said opening comprising a flexible member normally extending across said opening and across one of said ends, means for guiding said flexible member relative to said opening comprising stationary guide elements spaced from said top face and arranged adjacent the edges of said opening for guiding and supporting the edges of said flexible member, a projection on one end of said flexible member for withdrawing it from closing position with relation to said opening and a plate spanning said opening for supporting said flexible member intermediate the guiding edges thereof when said flexible member is in closed position, said plate being removable from such spanning position when said flexible member is open.

CHARLES WEEKS.
